(57) **CLAIM**

The ornamental design for a motorcycle blazer, as shown and described.

DESCRIPTION

Fig. 1.1 is a perspective view of a motorcycle blazer showing our new ornamental design;

Fig. 1.2 is a front view thereof;

Fig. 1.3 is a rear view thereof;

Fig. 1.4 is a first side view thereof;

Fig. 1.5 is a second side view thereof;

Fig. 1.6 is a top plan view thereof; and

Fig. 1.7 is a larger-scale perspective view of a detail thereof. The broken lines depict environment and form no part of the claim.
